[57] CLAIM

The ornamental design for a eyewear products support for a display tray, as shown and described.

DESCRIPTION

FIG. 1 is a top plan view of our new design for a eyewear products support for a display tray;

FIG. 2 is a right side view thereof;

FIG. 3 is a left side view thereof;

FIG. 4 is a front elevational view slightly turned at an angle; and,

FIG. 5 is a top right front perspective view thereof.

The portion of the drawings shown in dotted lines is for illustrative purposes only for assisting in understanding the new design set forth herein and, therefore, forms no part of the new design.
